BREATHABLE GAS REGULATING APPARATUS

Robert Kimes, Culver City, Robert L. Kesler, Pacific Palisades, and Stanley J. Mitchell, Los Angeles, Calif., assignors to The Garrett Corporation, Los Angeles, Calif., a corporation of California

Application September 8, 1953, Serial No. 378,856

21 Claims. (Cl. 128—142)

The present invention relates generally to breathing apparatus and relates more specifically to apparatus enabling the user to breathe both above and beneath the surface of water, in poisonous atmospheres, at high altitudes, suitable for use in emergency resuscitation.

Heretofore, breathing apparatuses designed for use in situations similar to those for which the present device is to be used have had inherent inadequacies such as, for example, uncomfortable or prohibitive resistance to breathing, a steady increase in such resistance as the breathable gas supply was exhausted, dangerous conditions resulting from apparatus failure and failure to provide sufficient warning to the user of the approach of exhaustion of the breathable gas supply. Additionally, prior devices have often been extremely heavy, cumbersome and difficult to maintain in operating condition and adjust for optimum performance. Furthermore, a considerable amount of re-breathing of exhalation products has occurred in prior devices of this character, such re-breathing being often harmful from a physiological standpoint.

Accordingly, it is an important object of the present invention to provide breathing apparatus which will overcome the beforementioned difficulties experienced in connection with prior breathing devices.

It is another important object of the present invention to provide a unitary, light weight, reliable, and efficient breathing apparatus wherein the breathing resistance is maintained at a substantially constant, low level throughout the entire useful period during which compressed breathable gas of varying pressure is utilized.

A further object of the present invention is to provide a breathing apparatus of the type described, wherein substantially no mixing of fresh breathable gas with exhalation products occurs.

A still further object of the present invention is to provide a breathing apparatus wherein means are provided to interrupt the flow of breathable gas from a source when the gas source approaches exhaustion, thereby to warn the user of the limited gas supply still available and to permit manual operation of a suitable valve for admitting the balance of the breathable gas to the breathing apparatus, thus providing an additional period of use during which time the user may seek a breathable ambient atmosphere.

It is another object of the present invention to provide a check valve arrangement for conducting exhalation products to ambient atmosphere, means being provided to prevent inadvertent reverse gas flow due to surging of the ambient medium, such as liquid or the like, and for preventing admission of such ambient medium to the respiration system of the user.

Other and further important objects of the present invention will become apparent from the disclosures in the following detailed description, appended claims and accompanying drawings, wherein:

2

Fig. 1 is a transverse sectional view of the breathing apparatus of the present invention;

Fig. 2 is an enlarged fragmentary sectional view showing the regulating mechanism in the position assumed during inhalation;

Fig. 3 is a sectional view showing portions of the gas reserve valve and taken substantially as indicated on line 3—3 Fig. 2;

Fig. 4 is a fragmentary sectional view showing portions of the present regulating mechanism in the position assumed during exhalation;

Fig. 5 is a top plan view of the present apparatus with portions cut away;

Fig. 6 is a graph illustrating the breathing resistance encountered in prior breathing devices; and

Fig. 7 is a graph similar to Fig. 6 showing the breathing resistance of the present breathing apparatus.

Referring primarily to Fig. 1 of the drawings, the breathing apparatus of the present invention is shown as indicated generally at 10. In general, the apparatus includes a regulator 11 that is attached by any suitable means to a source of breathable gas such as, for example, a tank 12. The regulator 11 is connected, by means of a flexible non-collapsing inhalation conduit 13 and a similar exhalation conduit 14, to a suitable mouthpiece indicated generally at 15. The conduits 13 and 14 have sufficient length so that they may extend preferably about the shoulders of the user to insure freedom of movement without undue slack that would permit their becoming fouled in objects or structures passed by the wearer.

The regulator 11 includes a unitary body portion 16 that is provided with a first chamber 17 for receiving a breathable gas and a second chamber 18 for receiving exhalation products. The chamber 17 communicates with the inhalation conduit 13 by means of a passage 19 formed laterally in one side of the body 16, the outer end of which is formed with a boss 20 to which the conduit 13 is secured by means of a clamp 21. The chamber 18 communicates with the conduit 14 by means of a passage 22 that is formed laterally in the other side of the body 16 and terminates within a boss 23, the conduit 14 being secured thereto by means of a clamp 24. A partition 25 is positioned in a recess 26 formed in the bottom of the chamber 18 and is secured to the body portion 16 by means of a plurality of screws 27. The partition 25 thus separates and forms adjacent sides for the chambers 17 and 18.

The body 16 of the regulator includes a downwardly extending portion 28 (see also Fig. 2) that extends from the portion of the body forming the chamber 17. A nipple 29 is threadably disposed, as at 30, in the portion 28, and has an axial bore 31. The nipple 29 is secured to a fitting 32 of a supply tank shut-off valve 33 by means of a nut 34. A filter 35 may be positioned in the bore 31. Breathable gas from the tank 12 is conducted through the valve 33, filter 35 and bore 31 to a recess 36 in the portion 28.

A restricting passage 37 is formed radially outwardly from the recess 36, the outer end of this passage being provided with a conical seat 38 against which a closure member 39, of a gas reserve valve, indicated generally at 40, is adapted to rest. The closure member 39 is generally triangular in cross-section (see Fig. 2) and is slidably disposed in a laterally extending cylindrical bore 41 formed in a projection 42 from the portion 28 of the body 16.

A fitting 43, having an internal recess 44 that is of substantially the same diameter as the bore 41, is threadably disposed in the outer end of the projection 42. The fitting 43 is adapted to rotatably and slidably support a

shaft 45, the inner end of which is provided with an enlarged disc 46, there being a packing gland 47 disposed in the inner end of the bore 44 and about the shaft 45. The outer end of the fitting 43 has a cam surface 48 that is adapted to co-operate with a cam follower 49, formed on a lever 50, the shaft 45 extending through the lever 50 and being secured thereto by means of a nut 51. The disc 46 is provided with a peripheral groove 52, Fig. 3, that is adapted to co-operate with a stop tab 53 that extends toward the disc from the fitting 43 so as to lock the shaft in its axial position at each end of the travel of the lever 50 and provides a stop means to limit rotation of the lever. Thus, any effect of pressure acting on the disc 46 is eliminated.

A pair of compression springs 54 and 55 are disposed respectively between the enlarged disc 46 of the shaft 45 and the closure member 39, and between a portion of the packing gland 47 and the disc 46. A lanyard or push rod 56 (Fig. 1) is secured to the outer end of the lever 50, as by a nut and bolt 57, the construction of the gas reserve valve being such that upon rotation of the lever 50 by the lanyard 56, the cam surface 49 will rotate against the cam surface 48 thereby to withdraw the shaft 45, thus compressing the spring 55 and relieving the compressive force of the spring 54, this action being for a purpose to be hereinafter more fully described.

Under normal conditions, the closure member 39 is maintained in a closed position, with respect to the outer end of the restricted passage 37, by action of the compression spring 54. The force of the breathable gas acting upon the closure member 39 acts on all sides thereof and is balanced thereabout with the exception of pressure acting upon the relatively small area of the end of the portion 38 when the member is closed. The force of the spring 54 is sufficient normally to overcome the force of the gas acting upon the end of the portion 38. Under certain conditions to be hereinafter more fully discussed, the pressure differential existing across closure member 39 will be such as to create a proportionally heavier force on the end of the portion 38 than is normally present, thus to overcome the force of the spring 54, causing compression thereof and opening of the closure member 39 to permit the flow of gas through the restricted passage 37 and into the inner end of the bore 41, as shown in Fig. 2.

An angularly disposed passage 58 is adapted to conduct the breathable gas from the inner end of the bore 41 to the inner end of a recess 59 formed axially in the body portion 28 adjacent the chamber 17. A reduced diameter recess 60 extends downwardly from the bottom of the recess 59.

A movable element 61 has cylindrical portions 62 and 63 that are slidably disposed in the recesses 59 and 60, respectively. A pair of sealing rings 64 and 65 are disposed about the portions 62 and 63 to provide a seal between the element 61 and the body portion 16. The axial length of the portion 62 is slightly shorter than the axial depth of the recess 59, so as to present an annular shoulder 66 that defines a pressure differential area that may be acted upon by the pressure of the breathable gas being admitted to the inner end of the recess 59. The element 61 is provided with a lateral bore 67 that communicates with the inner end of the recess 59 and with an axial bore 68 through the element 61, the outer end of the bore 68 being provided with a conical valve seat 69 that is adapted to co-operate with a metering valve member 70. The valve seat 69 together with the element 61 may move relative to the body of the apparatus and may be termed a "floating" valve seat for the purpose of description.

The metering valve member 70 has a conical tip, or operating end portion 71 that may be made from "Nylon," or the like, for example, this portion being formed with a cylindrical extension 72 at the apex thereof, the portion 71 and extension 72 being adapted

to be received in the seat of the bore 68, the conical surface of the portion 71 co-operating with the matching conical surface on the valve seat 69. When the valve 70 is seated, as shown in Figs. 1 and 4, the extension 72 extends into the end of the bore 68 adjacent the conical seat 69. The construction of the operating end of the valve member 70 is such that a positive occlusion of the passage 68 is provided. When the valve member 70 is closed, the pressure differential area on which the gas within the passage 58 is acting is maintained at a constant value due to the protrusion of the extension 72 into the bore 68. It may be seen that as the valve member 70 is moved from its seat 69, the extension 72 must first clear the outer end of the bore 68, thus presenting a large aperture for the flow of the breathable gas from the bore 68. The relatively large contact area between the portion 71 and the valve seat 69 further greatly reduces "cold flow" and/or wear of the material of the portion 71 and insures longer, trouble-free operating life for the unit.

The shank of the valve member 70 extends upwardly through an axially disposed opening 73 in the partition 25 and into the chamber 18. A compression spring 74 is disposed about the shank of the valve member 70 between the partition 25 and the head portion of the valve member, thereby to urge the valve member toward the valve seat 69. A second compression spring 75, having a greater force than that of the spring 74, is disposed between the partition 25 and a flange 76 formed on the element 61, this second compression spring acting to oppose the force of the breathable gas acting upon the area 66 in a manner and for a purpose to be hereinafter more fully described.

A respiration pressure responsive flexible diaphragm 82 provides a movable wall for one side of the chamber 18, this diaphragm being clamped between the body portion 16 and a protective cap 83 by screws 84, Fig. 5. The diaphragm 82 is provided with upper and lower backing plates 85 and 86 that are secured to each other and to the diaphragm by rivets 87. An enlarged opening 88 is provided through the central area of the diaphragm 82 and backing plates 85 and 86 for reception of a bushing 89. The bushing 89 may be of semi-flexible material such as rubber, for example, and provided with a cylindrical portion 90 that is adapted to be received in the opening 88, there being an annular flange 91 extending over the backing plate 86 adjacent the periphery of the opening 88. The bushing 89 has an enlarged annular portion 92 that is adapted to extend over the surface of the backing plate 85. An axially extending annular flange 93 is formed on the periphery of the portion 92, this flange having outwardly projecting tabs 94. The outer surface 95 of the bushing 89 has a conical configuration against which a normally closed disc check valve member 96 is adapted to normally lie. The check valve member 96 is provided with a central stem 97 that has an enlargement 98. The stem 97 projects through a central opening 99 in the bushing 89, the portion 98 being received in an enlarged recess 100 in the inner side of the bushing 89. The bushing 89 is further provided with a plurality of axially extending fluid flow passages 101 to provide means for venting exhalation products from the chamber 18 to ambient atmosphere or the surrounding fluid medium. These exhalation products escape through the passages 101, past the check valve member 96 and out through the cap 83 by way of openings 102 extending through the cap 83.

It may be seen that the flange 93, formed in the bushing 89 and surrounding the flexible check valve member 96, serves to prevent the possible wash or surge of the ambient fluid medium from unseating this valve member and flowing into the chamber 18. The periphery of the valve member 96 is thus protected against being lifted in a manner tending to reverse its position, or cause malfunction thereof.

The check valve member 96 may be made from any suitable flexible material such as rubber, for example. Upon outward movement of the diaphragm 82 away from the chamber 18, the valve member 96, together with bushing 89, is carried outwardly, the tabs 94 limiting outward movement of the bushing and diaphragm by ultimate contact with the inner surface 103 of the cap 83. It may be seen that the bushing 89, together with the flexible check valve member 96, effectively forms a unitary structure, the inner end portion of the stem 97 being pulled through the bore 99 during assembly by means of an elongated portion (not shown) that is formed on the inner end of the stem 97 and subsequently removed after assembly. The bushing 89 merely snaps into place in the opening 88. In order to alleviate any possibility of the check valve member 96 adhering to the inner surface 103 of the cap 83, a plurality of radially extending ribs 104 are formed outwardly from a central boss 105 in the cap. These ribs thus interrupt an otherwise smooth surface of the cap.

The stem portion of the metering valve member 70 is provided with an enlargement formed by a washer 106 that is retained in place on the end of the stem by a suitable snap ring 107, for example. An annular ring 108 is formed outwardly toward the chamber 18 from the partition 25 and spaced radially from the valve member 70. This annular ring is provided with peripheral notches 109 that are adapted to receive levers 110, the inner ends of which are bent as at 111. The ends of the bent portions 111 are adapted to engage a radially inwardly directed surface of the portion 108 to retain the levers in place. The levers 110 are adapted to extend from the valve member stem, beneath the washer 106 and outwardly through the notches 109 to normally engage the diaphragm plate 86 as at 112, the engagement ends of the levers 110 being suitably rounded in order to reduce friction between these levers and the plate. It may be seen that when the diaphragm 82 moves inwardly toward the chamber 18, the levers 110 will be depressed, thus rocking these levers about the ring portion 108 and lifting the valve member 70 from its normal position on the seat 69. The comparative lengths of the levers 110 between the notches 109 and the engagement point 112 with the diaphragm plate 108, and between the notches 109 and the point of contact with the washer 106, is such as to provide a large mechanical advantage for lifting the valve member 70 from the seat 69.

The mouthpiece 15 has a transverse section 114 that is provided with a passage 115 therethrough. The inhalation and exhalation conduits 13 and 14 are secured to the portion 114 by suitable clamps 116. A laterally extending portion 117 is formed outwardly from the transverse portion of the mouthpiece and has a passage 118 therethrough that communicates with the passage 115. A flexible member 119 is attached to the outer end of the portion 117, this flexible member having an elongated laterally extending flange 120 that is adapted to be inserted beneath the lips of a user, there being bit portions 121 that are inserted between the teeth of the user so as to retain this mouthpiece in place. The user of the apparatus must breathe through his mouth when utilizing the present device, the eyes and nose generally being covered by a suitable face plate or mask. In this connection it is to be understood that the device may be used with a suitable mask having an integral mouthpiece or with a mask wherein the breathable gas is delivered in such a manner as to permit breathing through either the nose or mouth.

During operation and use of the present breathing apparatus, in, for example, situations requiring submersion in a liquid, it is customary that the device be secured to the back of the user, with the regulator 11 disposed substantially at the level of the lungs of the user. When placed in this manner, the surrounding fluid medium will exert on the diaphragm 82 and on the lungs of the user

substantially the same pressure even though the user may assume various attitudes.

The conduits 13 and 14 are adapted to extend over the shoulders of the individual and the mouthpiece 15 is retained in the mouth as hereinbefore described. The breathable gas in the tank 12 may initially be compressed to a pressure of 2000 p. s. i., for example, and the breathable gas may either be compressed air, oxygen or other mixtures of gases as may be necessary to sustain life. As previously described, the device provides a flow path or restricted passage for the breathable gas from the source to a point of use, this passage being defined by the bore 31, recess 36, bores 37 and 41, passage 58, and bores 67 and 68 to the chamber 17, and from the chamber 17 by way of the passage 19 and inhalation conduit 13 to the mouthpiece 15. Assuming that the initial pressure of the gas supply is 2000 p. s. i., a pressure drop is experienced across the closure member 39 so that the gas existing at the inner end of the bore 41 will be at approximately 1700 p. s. i. The gas at this reduced pressure is transmitted through the passage 58 and into the inner end of the recess 59, thereafter to act upon the area 66 of the element 61, thereby to move the element 61 against the compression of the spring 75 to the position shown in Fig. 1. Inward movement of this element is limited by a plurality of downwardly extending fingers 126 from the partition 25 and spaced radially from the valve member 70, these fingers being adapted for engagement with the flange 76 on the element 61.

Upon inhalation, a reduction in the pressure existing in the conduits 13 and 14 as well as in the chambers 17 and 18 is created, thus causing the diaphragm 82 to be moved inwardly toward the chamber 18 to depress the levers 110 and lift the valve member 70 from the seat 69 as illustrated in Fig. 2. As inhalation is started and as the valve member 70 is lifted from the seat 69, a differential in pressure is created across the closure member 39, thereby, as hereinbefore described, causing the closure member 39 to move in a direction to compress the spring 54 and permit flow from the bore 37 through the bore 41 and into the passage 58. Opening and closing of the closure member 39 occurs therefore with each inhalation and exhalation cycle. Thereafter a metered amount of the breathable gas is admitted to the chamber 17 and conduit 13 by way of restricted passages defined by the bores 67 and 68. It may be seen that the diaphragm 82 is exposed on one side to the pressure in the chamber 18, this pressure being substantially the same pressure as existing in the lungs of the user, and on the other side to the pressure of the surrounding fluid medium, thereby to maintain a pressure in the lungs which substantially equals that of the surrounding fluid medium, thus preventing possible damage to the lungs from differential pressures that might otherwise exist. At the end of each inhalation, the diaphragm will return to a neutral position, as shown in Fig. 1, to permit the valve member 70 and closure member 39 to close.

Upon exhalation, exhalation products are conducted through the passages 118 and 115 in the mouthpiece 15, into the exhalation conduit 14 and chamber 18, whereupon a differential in pressure is created across the diaphragm 82 to cause this diaphragm to move outwardly until the tabs 94 engage the inner surface 103 of the cap 83, the diaphragm assuming the position indicated in Fig. 4. Exhalation gases will now flow through the passages 101, past the periphery of the flexible valve member 96, into the interior of the cap 83 and out through the openings 102 to ambient atmosphere or the surrounding fluid medium. It is to be noted that substantially no mixing of the breathable gas with the exhalation products is encountered, with the exception of the gas existing in the very small area of the passage 115 in the mouthpiece 15, thus reducing the amount of carbon dioxide present in the inhaled gas to an absolute minimum

and alleviating the adverse physiological effects that may accompany re-breathing of exhalation products.

In prior devices designed to accomplish a purpose similar to that of the present invention, as the available pressure of the breathable gas was reduced through consumption thereof, it often became increasingly difficult for the user to breathe because of the force of gas pressure acting on the metering valve decreasing with respect to the substantially constant spring force urging the valve member toward closed position. In other devices, breathing resistance has been very high when the gas supply pressure was high and was reduced slightly as the supply pressure was reduced. Such devices are very unsatisfactory as considerable fatigue is experienced by the user in an effort to overcome high breathing resistance. This undesirable condition is corrected in the present apparatus, the force of the decreasing pressure of the breathable gas upon the pressure differential area 66 being correspondingly reduced in opposition to the force of compression spring 75. Hence, the element 61 is permitted to float or move toward a position approximating that shown in Fig. 2, movement of the element 61 carrying the valve seat 69, in a floating manner, farther away from the partition 25, thus relaxing the spring 74 and reducing the force thereof tending to seat the valve member 70 on the valve seat 69. Movement of the element 61 is such that the force of the spring 74 is maintained slightly higher than the force exerted by the compressed breathable gas upon the extension 72 of the valve member, thus maintaining uniform breathing resistance. This substantially constant resistance to breathing is shown clearly in Fig. 7 by the curve 130, the breathing resistance being maintained well below a desirable value of 2.7 inches of water maximum differential pressure, and at a substantially constant level throughout the entire pressure range of the gas contained in the tank 12, from 2000 p. s. i. to approximately 550 p. s. i., this lower pressure existing when the element 61 engages the bottom of the chamber 17. This condition is contrary to the situation existing in prior devices, wherein such low maximum breathing resistance has either not been maintained or the breathing resistance increased rapidly throughout the entire period of use of the air in the supply tank. In Fig. 6, a curve 131 represents the situation existing in prior devices.

As the pressure of the breathable gas is reduced to 300 p. s. i., for example, and as the supply approaches exhaustion, the pressure differential across the closure member 39 is gradually reduced until this differential is insufficient to overcome the force of the spring 54 in closing the closure member 39, whereupon the flow of breathable gas to the recess 41 will be shut off, thus providing a warning to the user that the supply of gas is approaching exhaustion. Immediately, the lanyard 56 may be pulled to rotate the lever 50 to the position shown in Fig. 2, thus moving the shaft 45 outwardly by action of the cam surface 48 and cam follower 49, and relaxing the spring 54. This action reduces the force of the spring 54 and permits the closure member 39 to be unseated by the succeeding inhalation cycle. Thereafter, the closure member 39 remains open to enable free flow of gas to the passage 58. After such movement of the lever 50, and depending upon the physical condition of the user and the volume of the tank 12, five to eight minutes supply of breathable gas then remains, permitting the user to surface or to seek a breathable ambient atmosphere.

It may thus be seen that the present device adequately fulfills the objects set out hereinbefore and provides a mechanism that may be used in a variety of situations either under water or wherever unbreathable, contaminated or poisonous atmospheres are encountered. In all conditions of use, the device of the present invention is completely "fail-safe" in that breakage or malfunction of important parts would not result in danger to the user. For example, if either of the springs 54 or 55 in

the gas reserve valve should break, a free flow of gas would merely be delivered to the passage 58 and into the balance of the unit, some warning of the exhaustion of breathable gas thereafter being provided by increased breathing resistance near the point of gas exhaustion. If the compression spring 75 should fail, the force of the breathable gas acting upon the pressure differential area 66 would merely move the element 61 until the fingers 126 engage the flange 76, thus causing an increase in breathing resistance, this resistance still being acceptably low, as indicated by the curve 132 in Fig. 7, and breathing can be easily maintained. If the metering valve spring 74 should fail, a free flow of gas would be permitted to the chamber 17 until the pressure in the supply tank 12 dropped to a level that would be balanced by the reduced force of the broken spring 74 thus permitting the metering pin to resume its operation. In this condition, the excess gas flowing into the chamber 17 would be conducted through the inhalation conduit 13, through the passage 115 in the mouthpiece 15 and through the exhalation conduit 14, into the chamber 18 thereafter to flow into the surrounding fluid medium through the check valve 96. If such a condition should exist, approximately 15 minutes of uninterrupted breathing would still be available.

It is to be noted that the present device may be readily and easily serviced and may be maintained in proper working order without a great knowledge of such devices. There are no critical adjustments necessary for any of the components of the device and no calibration of portions or elements thereof is required. Additionally, the simple and rugged design of the present device will insure a considerably longer service life than that provided by prior similar units, there being relatively few parts that will wear, such possible wear being virtually eliminated by the present arrangement. Various components of the device may be replaced by the average individual without the necessity for returning the unit to the manufacturer.

We claim:

1. A breathable gas regulating device comprising: first passage means for conducting a breathable gas from a source to a point of use; a chamber in said device; second passage means for conducting expired gas from said point of use to said chamber; a check valve for controlling fluid flow from said chamber to the surrounding fluid; a movable wall forming one side of said chamber, said movable wall being subjected on one side to the pressure in said chamber and on the other side to the pressure of the surrounding fluid; valve means for controlling the flow of breathable gas through said first passage means; means for biasing said valve means toward a closed position; means operably associated with said movable wall for opening said valve means upon a reduction of the pressure in said second passage means and in said chamber thereby to permit flow of said breathable gas through said first passage means; and means operably associated with said valve means for substantially maintaining constant the force biasing said valve means toward a closed position and consequently the force required to open said valve means as the pressure of said breathable gas is reduced through use thereof.

2. A breathable gas regulating device comprising: first passage means for conducting a breathable gas from a source to a point of use; a chamber in said device; second passage means for conducting expired gas from said point of use to said chamber; a movable wall forming one side of said chamber, said movable wall being subjected on one side to the pressure in said chamber and on the other side to the pressure of the surrounding fluid medium; valve means for controlling the flow of breathable gas through said first passage means; means for biasing said valve means toward a closed position; means operably associated with said movable wall for opening said

valve means upon a reduction of the pressure in said second passage means and in said chamber thereby to permit flow of said breathable gas through said first passage means; and means responsive to a reduction in pressure of said breathable gas from said source to maintain at substantially a constant level the force biasing said valve means toward a closed position and consequently the magnitude of said reduction in pressure in said second passage means and in said chamber necessary to move said movable wall and open said valve means.

3. A breathable gas regulating device comprising: first passage means for conducting a breathable gas from a source to a point of use; a chamber in said device; second passage means for conducting expired gas from said point of use to said chamber; a movable wall forming one side of said chamber, said movable wall being subjected on one side to the pressure in said chamber and on the other side to the pressure of the surrounding fluid medium; a check valve for controlling the flow of gas from said chamber, said check valve being carried by said movable wall; valve means for controlling the flow of breathable gas through said first passage means; means for biasing said valve means toward a closed position; means operably associated with said movable wall for opening said valve means upon a reduction of the pressure in said second passage means and in said chamber thereby to permit flow of said breathable gas through said first passage means; and means responsive to a reduction in pressure of said breathable gas at said source to maintain at substantially a constant level the force biasing said valve means toward a closed position and consequently the magnitude of said reduction in pressure in said second passage means and in said chamber necessary to move said movable wall and open said valve means.

4. In a breathable gas regulating device: a regulator; a first chamber in said regulator for receiving a breathable gas from a source; valve means for controlling the flow of said gas into said first chamber; means resiliently urging said valve means toward a closed position; inhalation conduit means for conducting breathable gas from said first chamber to a point of use; a second chamber in said regulator; exhalation conduit means for conducting exhalation products from said point of use to said second chamber; a movable wall having one side exposed to the pressure in said second chamber, the other side of said wall being exposed to the pressure of the surrounding fluid medium; a check valve for controlling fluid flow from said second chamber; means operably interconnecting said movable wall and said valve means, whereby, upon inhalation, a reduction in pressure is created in said exhalation conduit means and in said second chamber thereby to move said movable wall and open said valve means to permit a flow of breathable gas into said first chamber and into said inhalation conduit means and means responsive to variations in pressure of the gas at the source to vary the effective force of the valve closing means, such effective force being varied in a predetermined manner relative to the variations in the gas pressure at the source.

5. In a breathable gas regulating device: a regulator; a first chamber in said regulator for receiving a breathable gas from a source; valve means for controlling the flow of said gas into said first chamber; means resiliently urging said valve means toward a closed position; inhalation conduit means for conducting breathable gas from said first chamber to a point of use; a second chamber in said regulator; exhalation conduit means for conducting exhalation products from said point of use to said second chamber; a movable wall having one side exposed to the pressure in said second chamber, the other side of said wall being exposed to the pressure of the surrounding fluid medium; a check valve for controlling fluid flow from said second chamber, said check valve being carried by said movable wall; means operably

interconnecting said movable wall and said valve means, whereby, upon inhalation, a reduction in pressure is created in said exhalation conduit means and in said second chamber thereby to move said movable wall and

5 open said valve means to permit a flow of breathable gas into said first chamber and into said inhalation conduit means and means responsive to variations in pressure of the gas at the source to shift the closing point of said valve means and thus vary the effective force of said
10 valve closing means.

6. In a breathable gas regulating device: a regulator; a first chamber in said regulator for receiving a breathable gas from a source; valve means for controlling the flow of said gas into said first chamber; a floating valve

15 seat associated with said valve means; inhalation conduit means for conducting breathable gas from said first chamber to a point of use; a second chamber in said regulator; exhalation conduit means for conducting exhalation products from said point of use to said second chamber.

20 ber; a movable wall having one side exposed to the pressure in said second chamber, the other side of said wall being exposed to the pressure of the surrounding fluid medium; a check valve for controlling fluid flow from said second chamber; and lever means operably inter-

25 connecting said movable wall and said valve means, whereby, upon inhalation, a reduction in pressure is created in said exhalation conduit means and in said second chamber thereby to move said movable wall inwardly toward said second chamber and open said valve 30 means to permit a flow of breathable gas into said first chamber and into said inhalation conduit means.

7. In a breathable gas regulating device: a regulator; a first chamber in said regulator for receiving a breathable gas from a source; valve means for controlling the

35 flow of said gas into said first chamber; a movable seat associated with said valve means, said seat being positioned in response to the pressure of said breathable gas; inhalation conduit means for conducting breathable gas from said first chamber to a point of use; a second cham-

40 ber in said regulator; exhalation conduit means for con-
ducting exhalation products from said point of use to said
second chamber; a movable wall having one side exposed
to the pressure in said second chamber, the other side of
said wall being exposed to the pressure of the surrounding
45 fluid medium; a check valve for controlling fluid flow

from said second chamber; and means operably interconnecting said movable wall and said valve means, whereby, upon inhalation, a reduction in pressure is created in said exhalation conduit means and in said second chamber thereby to move said movable wall and open said valve means to permit a flow of breathable gas into said first chamber and into said inhalation conduit means.

8. In a breathable gas regulating device: a regulator; a first chamber in said regulator for receiving a breathable gas from a source; valve means for controlling the flow of said gas into said first chamber; a movable seat

now of said gas into said first chamber, a movable seat associated with said valve means; spring means normally urging said seat away from said valve means; means to oppose the force of said spring means in response to the pressure of said breathable gas; inhalation conduit means for conducting breathable gas from said first chamber to

for conducting breathable gas from said first chamber to a point of use; a second chamber in said regulator; exhalation conduit means for conducting exhalation products from said point of use to said second chamber; a 65 movable wall having one side exposed to the pressure in said second chamber, the other side of said wall being

70 said second chamber, the other side of said wall being exposed to the pressure of the surrounding fluid medium; a check valve for controlling fluid flow from said second chamber; and means operably interconnecting said movable wall and said valve means, whereby, upon inhalation, a reduction in pressure is created in said exhalation conduit means and in said second chamber thereby to move

75 said inhalation conduit means.

9. A breathable gas regulating device comprising, in combination: a regulator body; a first chamber in said body; passage means for conducting a compressed breathable gas from a source to said first chamber; a valve member in said passage means; a movable element associated with said valve member; said element having a valve seat adapted for operable association with said valve member; first spring means normally urging said valve member toward said valve seat; a pressure differential area formed on said element, said area being subjected to the pressure of said breathable gas from said source, thereby to urge said element and said valve seat toward said valve member; second spring means acting on said element in a direction to oppose the force of said breathable gas on said pressure differential area; an inhalation conduit for conducting said breathable gas from said first chamber to a point of use; a second chamber formed in said body; an exhalation conduit for conducting exhalation products from said point of use to said second chamber; a diaphragm forming one wall of said second chamber, said diaphragm having one side exposed to the pressure in said second chamber and the other side exposed to the pressure of the surrounding fluid medium; a check valve for controlling fluid flow from said second chamber; and means operable by movement of said diaphragm in response to an inhalation produced reduction in pressure in said exhalation conduit and in said second chamber to lift said valve member from said valve seat, thereby to permit a flow of breathable gas into said first chamber and into said inhalation conduit.

10. A breathable gas regulating device comprising, in combination: a regulator body; a first chamber in said body; a source of compressed breathable gas; passage means for conducting said breathable gas from said source to said first chamber; a valve member in said passage means; a movable element associated with said valve member, said element having a valve seat adapted for operable association with said valve member; first spring means normally urging said valve member toward said valve seat; a pressure differential area formed on said element, said area being subjected to the pressure of said breathable gas from said source, thereby to urge said element and said valve seat toward said valve member; second spring means acting on said element in a direction to oppose the force of said breathable gas on said pressure differential area; an inhalation conduit for conducting said breathable gas from said first chamber to a point of use; a second chamber formed in said body, said valve member extending into said second chamber; an exhalation conduit for conducting exhalation products from said point of use to said second chamber; a diaphragm forming one wall of said second chamber, said diaphragm having one side exposed to the pressure in said second chamber and the other side exposed to the pressure of the surrounding fluid medium; a check valve for controlling fluid flow from said second chamber; lever means operable by movement of said diaphragm in response to an inhalation produced reduction in pressure in said exhalation conduit and in said second chamber to lift said valve member from said valve seat, thereby to permit a flow of breathable gas into said first chamber and into said inhalation conduit.

11. A breathable gas regulating device comprising, in combination: a regulator body; a first chamber in said body; a source of compressed breathable gas; passage means for conducting said breathable gas from said source to said first chamber; a valve member in said passage means; a movable element associated with said valve member, said element having a valve seat adapted for operable association with said valve member; first spring means normally urging said valve member toward said valve seat; a pressure differential area formed on said element, said area being subjected to the pressure of said breathable gas from said source, thereby to urge said element and said valve seat toward said valve member; second spring means

70

acting on said element in a direction to oppose the force of said breathable gas on said pressure differential area; an inhalation conduit for conducting said breathable gas from said first chamber to a point of use; a second chamber formed in said body, said valve member extending into said second chamber; an exhalation conduit for conducting exhalation products from said point of use to said second chamber; a diaphragm forming one wall of said second chamber, said diaphragm having one side exposed to the pressure in said second chamber and the other side exposed to the pressure of the surrounding fluid medium; a check valve for controlling fluid flow from said second chamber, said check valve being carried by said diaphragm; and lever means operable by movement of said diaphragm in response to an inhalation produced reduction in pressure in said exhalation conduit and in said second chamber to lift said valve member from said valve seat, thereby to permit a flow of breathable gas into said first chamber and into said inhalation conduit.

12. A breathable gas regulating device comprising, in combination: a regulator body; a first chamber in said body; a source of compressed breathable gas; passage means for conducting said breathable gas from said source to said first chamber; a valve member in said passage means; a movable element associated with said valve member, said element having a valve seat adapted for operable association with said valve member; first spring means normally urging said valve member toward said valve seat; a pressure differential area formed on said element, said area being subjected to the pressure of said breathable gas from said source, thereby to urge said element and said valve seat toward said valve member; second spring means acting on said element in a direction to oppose the force of said breathable gas on said pressure differential area; an inhalation conduit for conducting said breathable gas from said first chamber to a point of use; a second chamber formed in said body, said valve member extending into said second chamber; an exhalation conduit for conducting exhalation products from said point of use to said second chamber; a diaphragm forming one wall of said second chamber, said diaphragm having one side exposed to the pressure in said second chamber and the other side exposed to the pressure of the surrounding fluid medium; a check valve for controlling fluid flow from said second chamber; lever means operable by movement of said diaphragm in response to an inhalation produced reduction in pressure in said exhalation conduit and in said second chamber to lift said valve member from said valve seat, thereby to permit a flow of breathable gas into said first chamber and into said inhalation conduit; and means positioned between said valve member and said source of breathable gas to interrupt the flow of said gas when the gas pressure of said source is reduced to a predetermined level.

13. A breathable gas regulating device comprising, in combination: a regulator body; a first chamber in said body; a source of compressed breathable gas; passage means for conducting said breathable gas from said source to said first chamber; a valve member in said passage means; a movable element associated with said valve member, said element having a valve seat adapted for operable association with said valve member; first spring means normally urging said valve member toward said valve seat; a pressure differential area formed on said element, said area being subjected to the pressure of said breathable gas from said source, thereby to urge said element and said valve seat toward said valve member; second spring means acting on said element in a direction to oppose the force of said breathable gas on said pressure differential area; an inhalation conduit for conducting said breathable gas from said first chamber to a point of use; a second chamber formed in said body, said valve member extending into said second chamber; an exhalation conduit for conducting exhalation products from said point of use to said second chamber; a diaphragm forming

one wall of said second chamber, said diaphragm having one side exposed to the pressure in said second chamber and the other side exposed to the pressure of the surrounding fluid medium; a check valve for controlling fluid flow from said second chamber; and lever means operable by movement of said diaphragm in response to an inhalation produced reduction in pressure in said exhalation conduit and in said second chamber to lift said valve member from said valve seat thereby to permit a flow of breathable gas into said first chamber and into said inhalation conduit; means positioned between said valve member and said source of breathable gas to interrupt the flow of said gas when the gas pressure of said source is reduced to a predetermined level; and manually operable means to override said interrupting means.

14. A breathable gas regulating device comprising, in combination: a unitary regulator body; a source of compressed breathable gas; a breathable gas receiving chamber formed in said body; a flow restricting passage intermediate said source of breathable gas and said chamber; an inhalation conduit for conducting said breathable gas from said receiving chamber to a point of use such as the respiration system of an individual; a valve member positioned in said breathable gas receiving chamber and adapted normally to occlude one end of said passage; a movable element associated with said valve member, said element having a valve seat adapted for operable association with said valve member; first spring means normally urging said valve member toward said valve seat; a pressure differential area formed on said element, said area being subjected to the pressure of said breathable gas from said source, thereby to urge said element and said valve seat toward said valve member; second spring means acting on said element in a direction to oppose the force of said breathable gas on said pressure differential area; an exhalation products receiving chamber formed in said valve body adjacent said breathable gas receiving chamber; a partition separating said chambers, said valve member extending from said breathable gas receiving chamber through said partition and having a portion disposed in said exhalation products receiving chamber; an exhalation conduit extending between said point of use to said exhalation products receiving chamber; a flexible diaphragm forming one wall of said exhalation products chamber, said diaphragm having one side exposed to the fluid pressure within said exhalation products receiving chamber and the other side exposed to the pressure of the surrounding fluid medium; a bushing positioned in substantially the central area of said diaphragm; fluid flow passages formed in said bushing, thereby to provide communication between said exhalation products chamber and an ambient medium; a flexible disc check valve associated with and adapted normally to occlude said passages in said bushing, thereby permitting fluid flow only outwardly from said exhalation products chamber; an annular ring extending from said partition intermediate said chamber, said ring being spaced radially from said valve member; an enlarged head on said valve member; a plurality of levers extending over said annular ring and beneath said enlarged head, said levers being adapted to engage and be depressed by said diaphragm upon movement thereof inwardly toward said exhalation products chamber, said inward movement of said diaphragm being caused by an inhalation produced reduction in pressure in said exhalation conduit and in said exhalation products chamber, thereby to lift said valve member from said seat to permit the flow of breathable gas from said source to said breathable gas receiving chamber and through said inhalation conduit to said point of use; a spring loaded closure member positioned in said restricted passage between said source of breathable gas and said valve member, said closure member being adapted to be opened by an inhalation created pressure differential thereacross, said closure member being adapted to shut off the flow of breathable gas from said source when the

pressure of said breathable gas from said source is reduced to a predetermined level; and means to manually reduce the spring force acting to maintain said closure member in its shut off position.

- 5 15. A breathable gas regulating device comprising, in combination: a unitary regulator body; a source of compressed breathable gas; a breathable gas receiving chamber formed in said body; a flow restricting passage intermediate said source of breathable gas and said chamber; 10 an inhalation conduit for conducting said breathable gas from said receiving chamber to a point of use such as the respiration system of an individual; a valve member positioned in said breathable gas receiving chamber and adapted normally to occlude one end of said passage; a 15 movable element associated with said valve member, said element having a valve seat adapted for operable association with said valve member; first spring means normally urging said valve member toward said valve seat; a pressure differential area formed on said element, said 20 area being subjected to the pressure of said breathable gas from said source, thereby to urge said element and said valve seat toward said valve member; means to limit movement of said element due to the force of said breathable gas; second spring means acting on said element in a 25 direction to oppose the force of said breathable gas on said pressure differential area; an exhalation products receiving chamber formed in said valve body adjacent said breathable gas receiving chamber; a partition separating said chambers, said valve member extending from 30 said breathable gas receiving chamber through said partition and having a portion disposed in said exhalation products receiving chamber; an exhalation conduit extending between said point of use to said exhalation products receiving chamber; a flexible diaphragm forming 35 one wall of said exhalation products chamber, said diaphragm having one side exposed to the fluid pressure within said exhalation products chamber and the other side exposed to the pressure of the surrounding atmosphere; a bushing positioned in substantially the central area of said diaphragm; fluid flow passages formed in said bushing, thereby 40 permitting fluid flow only outwardly from said exhalation products chamber; an annular flange surrounding the periphery of said flexible check valve to prevent inadvertent lifting of said flexible check valve from said fluid flow passages by surging of ambient atmosphere; an annular ring extending from said partition intermediate said 45 chambers; said ring being spaced radially from said valve member; an enlarged head on said valve member; a plurality of levers extending over said annular ring and beneath said enlarged head, said lever being adapted to engage and be depressed by said diaphragm upon movement thereof inwardly toward said exhalation products chamber, said inward movement of said diaphragm being caused by an inhalation produced reduction in pressure 50 in said exhalation conduit and in said exhalation products chamber, thereby to lift said valve member from said seat to permit the flow of breathable gas from said source to said breathable gas receiving chamber and through said inhalation conduit to said point of use; a spring loaded closure member positioned in said restricted passage between 55 said source of breathable gas and said valve member, said closure member being adapted to be opened by an inhalation created pressure differential thereacross, said closure member being adapted to shut off the flow of breathable gas from said source when the pressure of 60 said breathable gas from said source is reduced to a predetermined level; and means to manually reduce the spring force acting to maintain said closure member in its shut off position.

- 75 16. A breathable gas regulating device comprising, in combination: a unitary regulator body; a source of com-

pressed breathable gas; a breathable gas receiving chamber formed in said body; a flow restricting passage intermediate said source of breathable gas and said chamber; an inhalation conduit for conducting said breathable gas from said receiving chamber to a point of use such as the respiration system of an individual; a valve member positioned in said receiving chamber and adapted normally to occlude one end of said passage; a movable element associated with said valve member and slidably disposed in said regulator body, said element having a valve seat adapted for operable association with said valve member; first spring means normally urging said valve member toward said valve seat; a pressure differential area formed on said element, said area being subjected to the pressure of breathable gas from said source, thereby to urge said element and said valve seat toward said valve member; means carried by said element for limiting movement thereof due to said pressure of said breathable gas; second spring means acting on said element in a direction to oppose the force of said breathable gas on said pressure differential area; an exhalation products receiving chamber formed in said valve body adjacent said breathable gas receiving chamber; a partition separating said chambers, said valve member extending from said breathable gas receiving chamber through said partition and having a portion disposed in said exhalation products receiving chamber; and exhalation conduit extending between said point of use to said exhalation products receiving chamber; a flexible diaphragm forming one wall of said exhalation products chamber, said diaphragm having one side exposed to the fluid pressure within said exhalation products chamber and the other side exposed to the pressure of the surrounding fluid medium; a bushing positioned in substantially the central area of said diaphragm; fluid flow passages formed in said bushing, thereby to provide communication between said exhalation products chamber and the surrounding fluid medium; a flexible disc check valve, associated with and adapted normally to occlude said passages in said bushing, thereby permitting fluid flow only outwardly from said exhalation products chamber; an annular flange surrounding the periphery of said flexible check valve to prevent inadvertent lifting of said flexible check valve from said fluid flow passages, by surging of said fluid medium; an annular ring extending from said partition intermediate said chambers, said ring being spaced radially from said valve; an enlarged head on said valve member; a plurality of levers extending over said annular ring and beneath said enlarged head, said lever being adapted to engage and be depressed by said diaphragm upon movement thereof inwardly toward said exhalation products chamber, said inward movement of said diaphragm being caused by an inhalation produced reduction in pressure in said exhalation conduit and in said exhalation products chamber, thereby to lift said valve member from said seat to permit the flow of breathable gas from said source to said breathable gas receiving chamber and through said inhalation conduit to said point of use; a spring loaded closure member positioned in said restricted passage between said source of breathable gas and said valve member, said closure member being adapted to be opened by an inhalation created pressure differential thereacross, said closure member being adapted to shut off the flow of breathable gas from said source when the source pressure of said breathable gas is reduced to a predetermined level; and means to manually reduce the spring force acting to maintain said closure member in its shut off position.

17. A breathable gas regulating device comprising: first passage means for conducting a breathable gas from a source to a point of use; a chamber in said device; second passage means for conducting expired gas from said point of use to said chamber; a movable wall forming one side of said chamber, said movable wall being

70
75

subjected on one side to the pressure in said chamber and on the other side to the pressure of the surrounding fluid medium; valve means for controlling the flow of breathable gas through said first passage means; means operably associated with said movable wall for opening said valve means upon a reduction of the pressure in said second passage means and in said chamber thereby to permit flow of said breathable gas through said first passage means; and gas reserve valve means positioned upstream from said valve means for interrupting the flow of said breathable gas when the source pressure thereof is reduced to a predetermined level.

18. A breathable gas regulating device comprising: a source of breathable gas; a first passage for conducting breathable gas from said source to a point of use; an inlet valve in said first passage; a respiration responsive diaphragm, said diaphragm being exposed on one side to the pressure of surrounding fluid medium, the other side of said diaphragm being exposed to pressure of the gas delivered to the point of use; an exhalation valve having a discharge opening to said fluid medium adjacent said diaphragm; second passage means extending from said point of use to said exhalation valve; lever means interconnecting said diaphragm and said inlet valve whereby to open said valve upon an inhalation produced reduction in pressure on said other side of said diaphragm; and gas reserve valve means disposed in said first passage to limit flow of said breathable gas to said first passage when a predetermined low pressure limit of gas from said source is reached.

19. A breathable gas regulator comprising: a body formed for connection with a source of compressed gas and with conduits leading to and from a point of use; a diaphragm secured to said body for movement in response to pressure differences on opposite sides thereof, said diaphragm having a first side exposed to ambient fluid and a second side exposed to the pressure at the point of use of the gas; valve means in said regulator for controlling the flow of gas from said source into said regulator; lever means transmitting motion from said diaphragm to a portion of said valve means, movement of said diaphragm in response to pressure reductions on said second side serving to move said valve means in an opening direction; signal means in said body operative when the gas in said source approaches depletion to resist movement of a portion of said valve means in an opening direction; and manually operable means in said body for selectively rendering said signal means inoperative and relieving the resistance to movement of said valve means in an opening direction.

20. A breathable gas regulating device comprising: a source of breathable gas; a first passage for conducting breathable gas from said source to a point of use; an inlet valve in said first passage; a respiration responsive diaphragm, said diaphragm being exposed on one side to the pressure of the surrounding fluid medium, the other side of said diaphragm being exposed to pressure of the gas delivered to the point of use; an exhalation valve having a discharge opening to said fluid medium; second passage means extending from said point of use to said exhalation valve; means operatively connecting said diaphragm and said inlet valve to open the latter upon an inhalation produced reduction in pressure upon said other side of said diaphragm; gas reserve valve means disposed in said first passage; means resiliently urging said reserve valve means toward a closed position to resist the flow of breathable gas through said first passage; and selectively operated means for rendering said urging means inoperative and relieving such resistance to breathable gas flow.

21. A breathable gas regulating device comprising: a source of breathable gas; means forming a first passage for conducting breathable gas from said source to a point of use; means forming a floating valve seat in said passage forming means, said valve seat having a bore constituting part of said first passage; an inlet valve in said

first passage, said inlet valve having an extension of pre-determined cross-sectional area and length to enter and close the bore in said floating valve seat prior to engagement of the valve with said seat; means resiliently urging said inlet valve toward a closed position; a respiration responsive diaphragm, said diaphragm being exposed on a first side to the pressure of the surrounding fluid medium and on the second side to the pressure of the gas at the point of use; an exhalation valve having a discharge opening to said surrounding fluid medium; second passage means leading from said point of use to said exhalation valve; means operatively connecting said diaphragm and said inlet valve to open the latter upon an inhalation produced reduction in pressure upon said second side of said diaphragm; and means for applying breathable gas from said source to said floating valve seat forming means

to shift the same in response to variations in pressure at said breathable gas source, movement of said floating valve seat varying the effective force of said inlet valve urging means in a predetermined manner relative to the variations in gas source pressure.
